(57) **CLAIM**

The ornamental design for a cake holder, as shown and described.

DESCRIPTION

FIG. 1 is a perspective front view of a cake holder showing my new design;

FIG. 2 is a front elevation view thereof;

FIG. 3 is a rear elevation view thereof;

FIG. 4 is a left side elevation view thereof; the right side view being a mirror image thereof;

FIG. 5 is a top elevation view thereof; and,

FIG. 6 is a bottom elevation view thereof.

1 Claim, 3 Drawing Sheets
